UNITED STATES PATENT OFFICE.

JAMES B. HENDERSON, OF WASHINGTON, DISTRICT OF COLUMBIA.

FIGURE WHEELED TOY.

Application filed October 28, 1922. Serial No. 597,876.

To all whom it may concern:

Be it known that I, JAMES B. HENDERSON, a citizen of the United States, and a resident of Washington, in the District of Columbia, have invented new and useful Improvements in a Figure Wheeled Toy, of which the following is a specification.

This invention resides in a toy made in the likeness of an animal and so constructed that when drawn along a surface, it will execute a sinuous movement. It comprises only a few very simple parts, is easily assembled and quite effective in its purpose for the entertainment of children.

A specific embodiment is fully shown in the drawings, in which Figure 1 is a side view of the toy, Figure 2 a plan view, showing in dotted lines the sinuous movement that the toy executes; Figures 3 and 5, views showing a modified form of wheel, and Figures 4 and 6, still another form of wheel. Fig. 7 is a modified form of the toy, showing the middle T-shaped section reversed as to Fig. 1. Fig. 8 is the side view of Fig. 7, with part in section showing hinge, bolts and bushings.

Like reference characters designate like parts in the various views.

In the drawing, A represents the toy in its entirety. It is made in the particular embodiment shown in the form of a dog, and comprises a head section 1, an intermediate section 2, and a rear section 3. The three sections are rectangular in section and are made of plane surfaced rigid material, such as card board or wood. The middle section is made in the form of a T, and the two end sections have flanges which fit over the transverse horizontal portion of the T. The sections are interconnected by countersunk screws 4. Washers 4^a are inserted between sections to reduce wear. The sections are thus free to twist relatively of each other, as the screws fit loosely in the countersunk holes.

The ears 6 of the animal are made of flexible material so that they will flap as the animal makes its sinuous motions. To the legs 7 of the animal, are attached transverse bars 8. These serve as axles, upon which are mounted the wheels 9. These wheels are

carried by bolts or pins 10, threaded into ends of the bars 8. To the head section is attached the hook 11, to which may conveniently be attached the cord 12 for pulling the animal along a surface. In Fig. 8, the sections are interconnected by bolts 23, which fit loosely into bushings 24.

If the surface is quite irregular, the up and down movement of the wheels will be sufficient to cause the sections to twist relatively of each other. In order, however, to adapt the toy for similar sinuous movement along a flat surface, or to accentuate its movement even along an irregular surface, a special form of right front and left rear wheels are mounted angularly of their respective axles. Wheels 13 and 14 are bored at an angle, so that when mounted on their pins 10, they will stand at an angle to their axles. These wheels will have their entire surface, which is tangent to the ground, bearing on the ground. Wheels 15 and 16 are, however, formed with crowned surfaces so that they do not contact with the ground to as large an extent as wheels 13 and 14. This arrangement is necessary in view of the angular mounting of wheels 13 and 14. In Figures 3 and 5, wheels 17 and 18 merely have small cam portions 19 formed on their peripheries. In Figures 4 and 6, wheels 19 and 20 are in the form of two helical surfaces, making the wheels practically analogous to the wheels shown in Figure 2. Wheels 21 and 22 are therefore similarly given a crowned bearing surface.

The operation of the toy, is of course quite obvious. As it is drawn along some surface, it will be obliged to execute a sinuous movement because of the peculiar form and mounting of its wheels, and the sectional form of its body. As it executes its sinuous movement, it will cause the ears to flap, and thus, to a large extent, simulate the animal it represents.

Claim:

In a toy, a head section, rear section, and intermediate section, said sections being interconnected to permit of relative lateral movement between the sections, said sections being formed of rigid flat material, ears

of flexible material attached to said head section, said head and rear sections having legs, axles mounted on said head and rear sections, pins threadedly mounted on said axles, wheels carried by said pins, one front wheel and one rear wheel being mounted at an oblique angle to the

axles, and the other front and rear wheels being at right angles to the axles and having their bearing surfaces crowned, to cause a 10 sinuous movement of the toy when drawn along a surface.

In testimony whereof I affix my signature.

JAMES B. HENDERSON.
